United States Patent Office

Des. 193,002
Patented June 12, 1962

193,002

WALL BLOCK

Karl V. Brockman, Cleveland, Ohio, assignor to Stark Ceramics, Inc., Canton, Ohio, a corporation of Ohio

Filed Feb. 15, 1960, Ser. No. 59,393

Term of patent 14 years

(Cl. D18—2)

Fig. 2

Fig. 1

FIG. 1 is a front elevation of a wall block showing my new design; and

FIG. 2 is a section on the line 2—2, FIG. 1.

I claim:

The ornamental design for a wall block, substantially as shown.
